Primary Examiner — Jennifer L Rempfer*Assistant Examiner* — Adrienne Corra(74) Attorney, Agent, or Firm — Lowry Blixseth APC;
Scott M. Lowry(57) CLAIM

The ornamental design for a minimalist shoe as shown and described.

DESCRIPTION

FIG. 1 is a medial view of a minimalist shoe in accordance with the present invention; and,
FIG. 2 is a bottom view thereof.

The broken lines shown in the drawings represent portions of the minimalist shoe that form no part of the claimed design.
